UNITED STATES PATENT OFFICE.

ANNETTE B. TEBBS, OF NEW YORK, N. Y.

DESIGN FOR A MEDALLION OR SIMILAR ARTICLE.

No. 40,172.

Specification for Design.

Patented July 27, 1909.

Application filed May 22, 1909. Serial No. 497,814. Term of patent 3½ years.

To all whom it may concern:

Be it known that I, ANNETTE B. TEBBS, a citizen of the United States, residing at the city of New York, in the county of New York and State of New York, have invented a new, original, and ornamental Design for Medallions or Similar Articles, of which the following is a specification, reference being had to the accompanying drawing, forming part thereof, and which is a plan view of a medallion, showing my new design.

I claim:

The ornamental design for a medallion, or similar article, as shown.

ANNETTE B. TEBBS.
